FRANK DAVIS, OF BROOKLYN, NEW YORK, AND ANTON GROTHUS, OF HOBOKEN, NEW JERSEY

RIVETING MACHINE

Application filed January 27, 1928. Serial No. 249,826.

The present invention relates, generally, to machines for punching holes at lap seams of metal parts to be joined and for riveting lapped joints. The invention, more particularly, relates to machines for inserting rivets through lapped metal parts and heading over the rivets. The invention further relates to riveting machines having apparatus for carrying a plurality of rivets in position to be inserted through metal and for presenting them successively to inserting apparatus. The invention also relates to a method of inserting rivets through sheet metal.

An object of this invention is to provide a machine for punching a hole in a lapped sheet metal seam and inserting a rivet, simultaneously, the rivet to be inserted being used as a part of the punching apparatus; and a further object is to provide such a machine with means for inserting the rivet and heading the inserted rivet, in one operation.

Another object of the invention is to provide means for holding a plurality of rivets in position to be successively presented and held during a punching and riveting action.

Other objects and advantages of the invention will appear from the following description of an illustrative embodiment of the invention, from the description of the method of operation thereof, and from the drawings; and the invention also consists in the methods, devices and combinations and arrangements of parts set forth in the appended claims.

Throughout the drawings similar reference characters indicate corresponding parts.

Figure 1 is a front elevation view of a machine embodying the invention;

Figure 2 is a side elevation view of the same machine;

Figure 3 is a vertical sectional view in part of the machine of Figure 1, enlarged to show details of construction, and with a hole punching part and riveting part in raised position;

Figure 4 is a view similar to that of Figure 3 but with the hole punching part down in a punching position;

Figure 5 is an enlarged view, in part, of a rivet and work carrying means;

Figure 6 is a sectional view taken along the

line 6, 6 of Figure 5 and looking in the direction of the arrows; and

Figure 7 is a plan view showing details of a controlling means.

In the drawings the base 1 supports the vertical frame 2 which disposes above said base 1 the circular guide members 4, 6 and 8 which are vertically aligned one above the other. Slidably vertically in said guide members 4, 6 and 8 is the steel tube 10 which has a length greater than the extreme distance between said guide members 4 and 8 and which at its lower end carries the annular female punching die 12. At its upper end, above said guide member 4, said tube 10 carries the annular flange 14; and between said guide member 4 and said flange 14 said tube 10 carries fixed thereto the weight 13 which is in the form of a cylindrical block mounted on and about the tube 10. A pair of tension springs 16, 16 connecting said guide member 8 and said weight 13, serve as actuating means tending to move said tube 10 and the female punching die 12 downwardly.

In said tube 10 is slidably mounted the rod 20, the lower end 22 of which is formed as a riveting hammer. Above said flange 14, said rod 20 has fixed thereto a member 24 which at its upper end is frusto-conical and tapers downwardly from said rod 20 for a distance and then projects downwardly in a cylindrical portion at the lower end. Said member 24 at its lower face has formed therein a counter-bore 26 which is of such depth and diameter as to receive said flange 14 thereinto. A pair of tension springs 28, 28 are attached at their upper ends to the pins 30, 30 projecting from the front and the back, respectively, of said member 24, and said springs are attached at their lower ends to said guide member 4, said springs serve as actuating means tending to move said rod 20 and hammer 22 downwardly. At its upper end said rod 20 carries an upwardly projecting handle member 32. Above said guide member 4 and to the rear thereof said frame 2 carries, pivoted thereto, a pair of arms 34, 34 which project forwardly one on each side of said tube 10. Said arms 34 are of steel and tend to move toward each other, and are adapted

to move on their pivot from a position above said member 24 downwardly over the conical portion of the latter, whereby they will be spaced apart to permit the movement thereof downwardly past and below the cylindrical portion of member 24, below which they will move toward each other under the lower end of said member 24 in a manner and for a purpose hereinafter more fully described.

Below said arms 34 there is fixed to said frame 2 a bar 36 which extends outwardly and then upwardly between said arms 34 intermediate said frame 2 and said tube 10. Said bar 36 is of a width substantially the same as the diameter of said tube 10 and carries at its upper end the symmetrical cam member 38 which has a lower portion 40 which is of a width greater than the diameter of said flange 14 but smaller than the diameter of the cylindrical portion of said member 24. At its upper end said cam portion 40 merges into a cam portion 42 whose width is greater than the diameter of the cylindrical portion of said member 24. Between said frame 2 and said bar 36 a transverse rod 44 extends through said arms 34 and on the outer ends of rod 44 are mounted the compression springs 46, 46 which, bearing at their outer ends against the nuts 48, 48 on said rod 44, and at their inner ends against the outer sides of the respective ones of said arms 34, 34, tend to move said arms 34, 34 toward each other. Between rod 44 and said frame 2 said arms 34, 34 carry, pivoted thereto, the connecting rods 50, 50 which extend downwardly therefrom. At their lower ends said connecting rods 50, 50 are pivotally connected to the crank arms 52, 52 which extend laterally from and are fixed to the shaft 54 which is journaled in said frame 2; said connecting rods 50, 50 and crank arms 52, 52, being arranged in pairs one on each side of said frame 2. Fixed to said shaft 54 at one end thereof is the foot lever 56 to which extends downwardly alongside said base 1, and which at its lower end carries the foot pedal 58. At the opposite end of said shaft 54 is mounted the upwardly projecting arm 60, which at its upper end carries the counter-weight 62; said arm 60 being set on said shaft 54 so that in the normal position of said foot lever 58 said weight 62 is behind the axis of said journal 54, and is forward of this axis in the operated position of said foot lever 58. Above said foot pedal 58 said base 1 carries a guide 64 which extends along the direction of movement of said foot lever 56, and serves as a lateral guide therefor. Below said guide 64, said base 1 carries a leaf spring 66 which extends along the direction of movement of said lever 56, and is adapted to bear downwardly against a pin 68 fixed to said lever 56 and projecting inwardly therefrom. Said spring 66 is fixed at a point to the rear of said base 1 and has its

forward end free. At its lower side said spring 66 carries the stop member 72, which is inclined downwardly and backwardly to permit movement of said pin 68 past the same against the yielding pressure of said spring 66, but at its opposite side is inclined at an angle downwardly to catch and hold said pin 68 to restrain retractive movement of said lever 56 unless said spring 66 is pulled upwardly to move said stop 72 from the pin engaging position. The function of said stop 72 is hereinafter more fully set forth.

Said base 1, together with the support member 80, carries a bed plate 82 which extends longitudinally from a point below said tube 10 and rod 20. At its outer end said plate 82 carries a pair of clamp members 84, 86 which carry, in removably clamped relation, a horizontal mandrel 88 which extends therefrom in spaced relation above said plate 82, to a point below and beyond said tube 10 and rod 20. Along the upper side of said mandrel 88 is a rectangular channel or slot 90 which extends from under the tube 10 in one direction to a point near said clamp 86 and in the other direction to the end of mandrel 88. Positioned in said channel 90 is a rectangular sheath 92 which is pivoted to said mandrel 88 at the end near said clamp 86. This pivotal connection is made by means of a link 94 which has one end inserted into the end of sheath 92, and either fixed thereto or slidably removable therefrom, and has its other end pivoted to mandrel 88 by the pin 96. Said sheath forms bottom and side members 106 and has spaced apart longitudinal rims 98, 98 which extend along the top thereof from one end to the other. The distance between said rims 98, 98 is greater than the diameter of a rivet head which the machine is intended to use. Directly below said rod 20 said sheath has a hole 100 formed through its bottom, which hole is preferably of a diameter greater than that of the head of a rivet to be handled by the machine.

Slidably fitting in said sheath 92, and held therein by said rims 98, 98, is the rectangular rod 102 which has formed therein a plurality of spaced apart vertical holes 104, 104, each of a diameter to hold a rivet vertically therein with its head in easy sliding fit. Beneath said rod 20 said mandrel 88 supports a pin 106, which extends upwardly from the bottom of said channel 90 and through said hole 100 in the bottom of said sheath 92 for a short distance. This pin 106 serves as an abutment or support adapted to hold a rivet in opposition to the female die 12. Adjacent to said pin 106 is a pin 108 which extends through a hole 110 in the bottom of said channel 90, and has its head 112 in the counterbore 114 which extends from the bottom side of mandrel 88 to said hole 110. A compression spring 116 is positioned in said counterbore 114, and held in compressed relation against

said head 114 by the set screw 118, tends to hold said pin 108 in the uppermost position. Said spring 118, through engagement with the bottom of said sheath 92 by said pin 108, tends to hold said bar or rod 102 above the top end of said pin 106.

In the use and operation of the apparatus of the invention for riveting together lapped edges of sheet metal, the said rod 102 is slid into said sheath 92 and rivets 120, 120 are mounted head downwardly in each of said holes 104, 104, one of said holes 104 being aligned over said pin 106. A sheet iron pipe 122 can then be mounted over said mandrel 88 with its longitudinal edges 124, 126 in lapped relation. In this stage said lever 56 and foot pedal 58 are at an intermediate position in their movement with said shaft 54, and are held in such position by the spring 66 and catch 72, which latter engages said pin 68. In this position the bars 34, 34 have been raised to a point just below said cam member 38 to raise tube 10 and rod 20 to provide a working space thereunder on said mandrel 88, and said flange 14 is completely within said counter bore 26, and the forward ends of said bars 34, 34 engage the lower edge of said member 24 and the lower face of said flange 14 to support said tube 10 and rod 20 in partially raised position. The next step is to press down the outer end of the work over said bar 102 to bring the lapped edges 124, 126 down against the upwardly projecting end of a rivet 120 directly below said tube 10 and rod 20, the rivet being held from movement with the bar 102 by the pin 106. The foot pedal 58 is now moved further backwardly to bring said bars 34, 34 into operative engagement with the portion 40 of said cam member 38, whereby said bars 34, 34 are moved apart out of supporting engagement with said flange 14, which is thereby released. Said springs 16, 16 will then move said tube 10 downwardly with a sudden and sharp movement to bring said female punching die 12 downwardly against said lapped edges 124, 126 thereby causing said rivet 120 beneath tube 10, as supported by the fixed pin 106, to be pushed upwardly through said lapped edges 124, 126. The movement of said foot pedal 58 is continued, preferably in one motion, to cause said bars 34, 34 to pass over the upper part 42 of said cam 38 whereby they will be further moved apart to release said member 24, whereupon said springs 28, 28 will move said rod 20 downwardly with a sudden and sharp motion to bring said riveting hammer 22 against the end of the rivet 120 to head or crush said end over against the lapped edge 124.

The foot lever 58 is then drawn into the forward position, the toe of the foot being used to raise said spring 66 to permit said pin 68 to pass below said stop 72, and by this movement said bars 34, 34 are drawn down-

wardly over the conical portion of said member 24 and below the lower end of said member 24, whereupon said bars 34, 34 will be moved toward each other by said springs 46, 46 beneath said member 24 and also beneath said flange 14. Said bar 102 is then released from downward pressure whereby said spring 116 will press said sheath 92 to clear the lower end of said bar 102 from the upper end of said pin 106. Said foot lever 58 is then moved back until said pin 68 passed beyond said stop 72 to raise said die 22 and hammer 12 from the work; and spring 66, through engagement of pin 68 and stop 72, will hold lever 56 at this position. The work is then moved outwardly on mandrel 88 toward the next riveting point. Bar 102 is also moved outwardly in sheath 92 until the hole 104 with which pin 106 has been in engagement has moved from over pin 106 and pressure downwardly is applied to the work and bar 102 and the outward movement thereof continued until the next hole 104 comes in engagement with said pin 106, whereupon the downward pressure is used to move the lapped edges 124, 126 into engagement with the upper end of the rivet 120 in this next hole 104. The foot lever 58 is again moved backwardly as before to successively release said lever 10 and rod 20 to cause this next rivet to be inserted through the lapped edges and to head the rivet thereon. This sequence of operation is continued for as many rivets as are desired to be inserted and riveted in place.

We claim:

1. In combination in a punching and riveting machine, a female punching die and a riveting hammer both movable along a given line into and out of operative position; and a workholder in operative relation to said female die and hammer; said workholder comprising a longitudinal sheath having openings through opposite walls thereof aligned with said female die and hammer; a bar in said sheath having rivet carrying openings therethrough and movable longitudinally in said sheath to bring its said openings severally into registry with said openings in said sheath; a pin on the side of said sheath opposite from said female die and hammer and aligned with said openings in said sheath, said pin being adapted to support a rivet in opposition to the effective strokes of said female die and hammer.

2. In combination in a punching and riveting machine, a female punching die and a riveting hammer both movable along a given line into and out of operative position; and a workholder in operative relation to said female die and hammer; said workholder comprising a longitudinal mandrel aligned across the line of movement of said female die and hammer; a longitudinal sheath on said anvil on the side facing said female die and hammer, said sheath having openings

through opposite walls thereof aligned with said female die and hammer; a bar in said sheath having rivet carrying openings therethrough and being longitudinally movable in said sheath to bring its said rivet carrying openings severally into registry with said openings in said sheath; a pin mounted on said mandrel opposite said hammer and female die and adapted to support a rivet in opposition to the effective strokes of said female die and hammer; said sheath being movable toward and from said pin to bring said bar out of and into engagement with said pin; said female die having a central opening therein adapted to press around a rivet mounted on said pin to cause said rivet to punch a hole through sheet metal mounted between the rivet and female die.

3. A workholder for riveting machines and the like, comprising, a mandrel having a longitudinal slot therein extending to a given end thereof, a pin extending up from the bottom of said slot near said given end, a longitudinal sheath in said slot pivoted to said mandrel at the end opposite to said given end of said mandrel for movement up and down in said slot, said sheath having an opening through the wall adjacent the bottom of said slot and into which said pin can extend and having a second opening through the wall opposite said first opening, a bar in said sheath longitudinally slid able therein and having openings therethrough which can be brought severally into registry with said openings in said sheath; said pin being of a length to extend to near the said second opening in said sheath when the latter is against the bottom of said slot, and said sheath and bar being movable on the pivot of said sheath to move the bottom of said bar over the end of said pin.

4. A workholder for riveting machines and the like, comprising a mandrel having a longitudinal slot therein extending to a given end thereof, a pin extending up from the bottom of said slot near said given end, a longitudinal sheath in said slot pivoted to said mandrel at the end opposite to said given end of said mandrel for movement up and down in said slot, said sheath having an opening through its wall adjacent the bottom of said slot and into which said pin can extend and having a second opening through the wall opposite said first opening; a bar in said sheath longitudinally slid able therein and having openings therethrough which can be brought severally into registry with said openings in said sheath; said pin being of a length to extend to near the end of said second opening in said sheath when the latter is against the bottom of said slot, and said sheath and bar being movable on the pivot of said sheath to move the bottom of said bar over the end of said pin; and means tending to

hold said sheath in spaced apart relation with respect to the bottom of said slot.

5. In combination in a punching and riveting machine, a female punching die and a riveting hammer both movable along a given line into and out of operative position; and a workholder in operative relation to said die and hammer; said workholder comprising a longitudinal sheath having openings through opposite walls thereof aligned with said die and hammer; a bar in said sheath having rivet carrying openings therethrough and movable longitudinally in said sheath to bring its said openings severally into registry with said openings in said sheath; a pin on the opposite side of said sheath from said die and hammer and aligned with said openings in said sheath, said pin being adapted to support a rivet in opposition to the effective strokes of said female die and hammer; means for raising said die and hammer together from said mandrel, means tending to move said die and said hammer toward said mandrel; and means for successively releasing said die and hammer for movement to said mandrel.

6. In combination in a punching and riveting machine, a female punching die and a riveting hammer both movable along a given line into and out of operative position; and a workholder in operative relation to said die and hammer; said workholder comprising a longitudinal sheath having openings through opposite walls thereof aligned with said die and hammer; a bar in said sheath having rivet carrying openings therethrough and movable longitudinally in said sheath to bring its said openings severally into registry with said openings in said sheath; a pin on the opposite side of said sheath from said die and hammer and aligned with said openings in said sheath, said pin being adapted to support a rivet in opposition to the effective strokes of said female die and hammer; means for raising said die and hammer together from said mandrel, separate means tending to move said die and said hammer toward said mandrel; and means for successively releasing said die and hammer for movement to said mandrel.

7. In combination in a punching and riveting machine, a female punching die and a riveting hammer both movable along a given line into and out of operative position; and a workholder in operative relation to said die and hammer; said workholder comprising a longitudinal sheath having openings through opposite walls thereof aligned with said die and hammer; a bar in said sheath having rivet carrying openings therethrough and movable longitudinally in said sheath to bring its said openings severally into registry with said openings in said sheath; a pin on the opposite side of said sheath from said die and hammer and aligned with said openings in said sheath, said pin being adapted

to support a rivet in opposition to the effective strokes of said female die and hammer; means for raising said die and hammer together from said mandrel, means tending to move die and hammer toward said mandrel; and means for successively releasing said die and hammer for movement to said mandrel; first said means being adapted to hold said die and hammer in the raised position.

10 8. In combination in a punching and riveting machine, a female punching die and a riveting hammer both movable along a given line into and out of operative position; and a workholder in operative relation to said die and hammer; said workholder comprising a longitudinal mandrel aligned across the line of movement of said die and hammer; a longitudinal sheath on said anvil on the side facing said die and hammer, said sheath having openings through opposite walls thereof aligned with said die and hammer; a bar in said sheath having rivet carrying openings therethrough and being longitudinally movable in said sheath to bring its said rivet carrying openings severally into registry with said openings in said sheath; a pin mounted on said mandrel opposite said hammer and die and adapted to support a rivet in opposition to the effective strokes of said female die and hammer; said sheath being movable toward and from said pin out of and into engagement with openings in said bar; means for raising said die and hammer together from said mandrel, means tending to move said die and said hammer downwardly against said mandrel; and means for successively releasing said die and hammer for movement toward said mandrel.

9. In a punching and riveting machine having an axially movable hollow punch tube with a circular punch on the end thereof and a riveting hammer movable longitudinally therein, in combination; actuatable means to raise said punch and hammer preparatory to punching work and heading over a rivet; spring means for moving said punch and hammer in operative direction; and means for successively releasing said punch and hammer for working movement.

10 10. In a punching and riveting machine, an axially movable tubular punch adapted to push sheet metal over a rivet or other projection to form an opening therethrough to receive the latter; a hammer rod mounted for movement through said punch along the axis thereof; said punch having a lifting abutment at its upper end; said hammer rod having a lifting abutment at its upper end which is recessed to receive the lifting abutment of said punch; means tending to move said punch and said hammer rod in operative direction; lifting means engageable with said lifting abutment of said punch to raise the latter and in turn raise said hammer rod preparatory to operative strokes thereof;

means for actuating said lifting means; yieldable means to hold said lifting means in engagement with said lifting abutments; and means in the operative path of movement of said lifting means adapted when engaged by the latter to disengage the same successively from said punch and hammer rod lifting abutments to successively release them for their operative strokes.

11. In a punching and riveting machine, an axially movable hollow punch adapted to push sheet metal over a rivet or other projection to form an opening therethrough to receive the latter, a hammer rod mounted for movement through said punch along the axis thereof; a lifting projection on the upper end of said punch; a lifting projection on the upper end of said hammer rod above the lifting projection of said punch; spring means operative to move said punch and said hammer rod in operative downward direction; vertically oscillatable lifting means engageable with said lifting projection of said punch to raise the latter and in turn said hammer rod preparatory to operative strokes thereof; said lifting means being also capable of lateral movement; means for yieldably holding said lifting means laterally moved toward said punch and hammer rod so as to engage said lifting projections thereof; means in the path of upward movement of said lifting means to laterally move and outwardly displace the latter successively, first, from engagement with said lifting projection of said punch, and thereafter from engagement with said lifting projection of said hammer rod, to successively release said punch and hammer rod subject to operation by their said spring moving means; said lifting projection on said hammer rod having a sloping surface at its upper end to guide said lifting means, when retracted to initial position, around said lifting projections and into returned lifting relation thereto; and means for operating said lifting means.

12. In a punching and riveting machine as defined in claim 11, a weight on said punch to serve as an auxiliary to the spring operating means thereof.

In testimony, that we claim the invention set forth above we have hereunto set our hands.

FRANK DAVIS.
ANTON GROTHUS.
